CONTAINER CLOSURE AND FORMING MEANS
THEREFOR

Guy O. Conner and Ernest H. Bock, Wheeling,
W. Va., assignors to Wheeling Steel Corpora-
tion, Wheeling, W. Va., a corporation of Dela-
ware

Application November 20, 1936, Serial No. 111,898

5 Claims. (Cl. 220—61)

This invention relates to a closure, particularly a closure for metal containers, means for applying the closure to the container and sealing it thereto, and means for releasing the closure for removal when desired.

Closures of various types have been provided for metallic receptacles heretofore. None of these, however, so far as we are informed, is suitable for certain special applications. Metallic beer kegs, for example, require a closure having a tight seal yet it is desirable that closures for such receptacles be easily applied and removed by relatively unskilled labor.

We have invented a closure, together with means for applying and removing it, which fully meets the requirements of this application and has other novel features, advantages and points of superiority over closures heretofore known which should adapt it for a wide range of uses.

20 In accordance with our invention, we provide an opening in a container, such as a beer keg, with a sleeve upstanding therefrom. The sleeve has an outwardly extending offset intermediate its ends and is adapted to receive a closure. If

25 the container is designed to make only a single trip, the closure may be sealed by curling over the edge thereof the extreme end of the sleeve. If the container is designed to make several trips, a split sealing collar is disposed around the sleeve 30 and the end of the collar is curled over the edge of the closure.

For sealing closures in accordance with our invention, we provide a tool comprising a collapsible chuck made up of a plurality of segmental fingers 35 adapted to engage under the shoulder or offset before mentioned. A cup is adapted to embrace and collapse the chuck, while a die carried on the cup moves axially of the chuck to curl the end of the sleeve. A manually operable toggle linkage 40 facilitates operation of the parts in the manner described.

This tool is described and claimed in our co-pending application Serial No. 186,833, filed January 25, 1938.

45 Our tool for releasing the closure comprises a bar having an arcuate recess in one end, terminating in a hook. The recess is adapted to receive the curled end of the sleeve and the hook 50 to engage the extreme edge thereof so that by pulling back on the bar, the curled-in edge is bent outwardly whereby the closure can be removed.

The details of our invention are illustrated on 55 the accompanying drawing and will be described below, the sealing tool being explained first. In the drawing:

Fig. 1 is a vertical sectional view through the sealing tool of our invention in normal position, 60 parts being shown in elevation;

Fig. 2 is a view similar to Fig. 1 showing the parts in advanced position;

Fig. 3 is a transverse sectional view along the line III—III of Fig. 2;

Fig. 4 is a sectional view through a modified form of closure;

Fig. 5 is a similar view showing another form of closure; and

Fig. 6 is an elevation of the closure-releasing tool.

The sealing tool of our invention comprises a pin 10 having a disc or plate 11 secured thereto adjacent one end. A plurality of segmental fingers or jaws 12 have hooked lower ends 13 and recessed upper ends 14 whereby they are carried on the edge of the disc 11. A cup 15 is adapted to embrace the fingers or jaws 12 and has a conical lower end 16 adapted to cooperate with similarly shaped portions of the fingers 12 to collapse them when the cup is moved downwardly from the position shown in Fig. 1 to that shown in Fig. 2. The disc 11 and fingers 12 thus constitute a collapsible chuck operable by advancement of the cup 15.

A curling die 17 is disposed within the jaws 12, 25 being supported from the cup 15 by screws 18. Studs 19 engage the die 17 and cup 15 and are effective to transmit thrust from the latter to the former. The disc 11 is provided with holes for the screws 18 and the studs 19.

30 Toggle links 20 are pivoted at 21 to the cup 15. Toggle links 22 are pivoted to the links 20 at 23 and at 24 to a bearing 25 secured to the pin 10 as by the rivet 26. A spring 27 normally holds the parts in the position illustrated in Fig. 1. Levers 35 28 extend upwardly from the links 22 and terminate in yoke-shaped handles 29. By pressing outwardly and downwardly on the handles 29, the toggle linkages 20 and 22 are extended, as shown in Fig. 2, to pull up on the jaws or fingers 12 and push down on the cup 15 and die 17.

The tool described above is particularly adapted for the sealing of a closure such as shown in Figs. 1 and 2. As there shown, a container 31, such as a beer keg, has an opening 32 in the wall 45 thereof. A sleeve 33 extends upwardly from the opening, the edge of the opening being curled around a bead formed on the inner end of the sleeve, as shown at 34. An outwardly extending offset or shoulder 35 is formed in the sleeve intermediate its ends. A closure 36 comprises a disc 37 having a peripheral flange 38 terminating in a bead 39. The closure is adapted to be placed over the opening 32 with a gasket 40 below it, the gasket and closure seating on the curled edge 55 34 of the opening 32.

A split sealing collar 41 is disposed over the sleeve 33, being expanded at the split to permit such disposition thereof. The collar 41 has an inwardly extending shoulder 42 adapted to en-

gage under the shoulder 35 of the sleeve 33. The outer end of the collar, furthermore, is curved inwardly to a slight extent, as shown at 43.

When the closure 36 and the collar 41 have been disposed as shown in Fig. 1, the sealing tool is disposed therearound as shown in dotted lines in Fig. 1. Outward and downward pressure on the handles 29 forces the cup 15 and die 17 downward. Downward movement of the cup 15 collapses the jaws 12, whereupon they engage under the shoulder 42 as shown in Fig. 2. As before stated, the shoulder 42 of the collar 41 engages under the shoulder 35 of the sleeve 33. When the jaws 12 have obtained a firm grip under the shoulder 42, and collapsed the collar 41 into snug peripheral engagement with the sleeve 33, the peripheral groove 17a of the die 17 engages the inwardly curved end 43 of the collar 41 and deforms it to the condition shown in Fig. 2, in which the end of the collar is fully curled inwardly and over the bead 39 on the closure 36, the grip of the jaws 12 under the shoulder 42 furnishing the reaction necessary for the deforming operation. The gasket 40 is compressed as shown in Fig. 2 by the downward pressure on the die 17 and a very tight seal is thus effected. The spring 27 restores the parts to the position shown in Fig. 1 when the pressure on the handles 29 is relieved. The jaws 12 being expanded, the tool may easily be removed from the sealed closure.

When the container has been delivered to the user of the contents thereof, the closure may readily be released for removal by the aid of the tool shown in Fig. 6. As there shown, the tool 35 comprises a bar 45 having a handle 46. The end of the bar has an arcuate recess 47 therein which terminates in a hook 48. An inclined slot 49 is also formed in the bar adjacent the end. When it is desired to release a closure, the end of the 40 bar is placed on the curled-in end of the collar 41 so that the hook 48 engages the edge thereof. Outward and downward pressure on the handle 46 bends the edge of the sleeve upwardly and by repeating this process at spaced points around 45 the closure, the collar 41 may be sufficiently bent outwardly and upwardly to release the closure 36. The slot 49 is designed to receive one of the split ends of the collar 43 so that the latter may be completely removed from the sleeve 33.

50 The closure shown in Figs. 1 and 2 is applicable to a container which is to be reused, since the sleeve 33 is not deformed by the application or removal of the closure and sealing collar 30. If a container is to be used only once, the end of the 55 sleeve 33 may be curled over the bead on the closure to seal it. An example of this type of construction is shown in Fig. 4. This seal is similar to that of Fig. 1 except that no collar 41 is employed and the sleeve 33' is made long enough to permit curling over the bead on the closure 36'.

Fig. 5 illustrates a further modified form of closure and seal. In Fig. 5, the sleeve 33'' has an outwardly flaring portion 50 which provides a 60 seat for a closure 51 having a conical portion 52. A gasket is provided between the closure and the flared portion 51 of the sleeve. The latter also has a shoulder intermediate its ends, as in the other forms of closure shown. The tools shown 65 in Figs. 1, 2 and 6 are adapted to sealing and unsealing closures of the types shown in Figs. 4 and 70 5 as well as that shown in Figs. 1 and 2.

It will be apparent from the foregoing description that the invention provides a simple yet effective means for closing filling openings in con-

tainers. The closing tool is particularly advantageous since no particular skill is required for its operation. It produces a tight effective seal, nevertheless, which at the same time is easily removable.

Although we have illustrated and described but one preferred form of tool and a few forms of closures, it will be apparent that the details shown may be varied without departing from the spirit of the invention or the scope of the appended 10 claims.

We claim:

1. A container having an opening, closure means comprising a sleeve having its base disposed about said opening and extending outwardly from the container and connected thereto, said sleeve having intermediate its ends a re-entrant peripherally thereof forming on its outer surface an outwardly projecting hook-shaped flange providing a grip for a sealing tool, said sleeve flaring outwardly intermediate the container and the hooked-shaped flange and forming a conical closure seat, and a closure positioned in said sleeve, the extreme end of the sleeve being curled over the edge of the closure.

2. A seal for a closure covering an opening in a container, comprising a tubular sleeve having an inturned bead at one end, about which the container wall adjacent said opening is curled to provide a closure seat, a closure on said seat, a reentrant offset intermediate the ends of said sleeve, providing a grip for a sealing tool, and means extending inwardly from said offset over the edge of said closure.

3. A container closure comprising an annular seat surrounding an opening in a container and having an exposed face lying generally in a plane perpendicular to the axis of the opening, a closure member having a portion resting upon said face and another portion extending generally outwardly of the container away from said seat generally in the direction of the axis of the opening and having a curled extremity, and means engaging the container and said generally outwardly extending portion of the closure member holding the closure member in place.

4. A container closure comprising an annular seat surrounding an opening in a container, a closure member engaging said seat and having a fastening means engaging bead and fastening means connected with the container extending generally outwardly of the container generally in the direction of the axis of the opening and engaging the fastening means engaging bead of the closure member to hold it in place, the fastening means having a tool engaging shoulder intermediate its ends.

5. A container having an opening, an annular bead surrounding said opening and forming a closure seat having an exposed face lying generally in a plane perpendicular to the axis of the opening, a closure member therefor, said closure member having a seat resting on said face, said closure member having a portion flaring outwardly and terminating in an annular bead offset from said seat and having an exposed face lying generally in a plane perpendicular to the axis of the opening, and fastening means connected with the container about said opening and extending outwardly therefrom and engaging said bead on said last-named exposed face thereof to hold the closure member in place.
